DESIGN FOR A CABINET

Irvin E. Berger, Chicago, Ill., assignor to National Steel Cabinet Co., Chicago, Ill., a corporation of Illinois

Application August 5, 1947, Serial No. 140,701

Term of patent 7 years

(Cl. D33—19)

To all whom it may concern:

Be it known that I, Irvin E. Berger, a citizen of the United States, and resident of Chicago, in the county of Cook and State of Illinois, have invented a new, original, and ornamental Design for a Cabinet, of which the following is a specification, reference being had to the accompanying drawing, forming a part thereof.

Fig. 1 is a perspective view of a cabinet, showing my new design.

Fig. 2 is a side elevational view thereof.

Fig. 3 is a top plan view thereof.

I claim:

The ornamental design for a cabinet, substantially as shown.

IRVIN E. BERGER.
